BRUSH-GEAR FOR DYNAMO-ELECTRIC MACHINES.

1,259,672.

Specification of Letters Patent. Patented Mar. 19, 1918.

Application filed February 16, 1917. Serial No. 148,930.

To all whom it may concern:

Be it known that we, HARRY D. ROHMAN, a citizen of the Republic of Switzerland, and FRANK R. PETERS, a citizen of Great Britain, both residing at New York city, in the county of New York and State of New York, United States of America, have invented certain new and useful Improvements in Brush-Gear for Dynamo-Electric Machines, of which the following is a specification.

Our invention relates to a brush gear or rigging for dynamo electric machines, such as dynamos or motors, although it is particularly directed to an improved brush rigging in dynamos subject to reversals in direction of rotation such as is the case with dynamos used for train lighting purposes. One of the primary objects of our invention is the provision of an improved brush gear or rigging which is an effective substitute for the special pole changing mechanism customarily employed in train lighting systems to maintain constant polarity in the external circuit. Another one of the more important objects of our invention resides in the provision of an improved brush gear wherein the difficulties usually encountered with the use of flexible leads for connecting the brushes with the main leads are obviated.

One of the more specific objects of our invention resides in the provision of an improved, simple, economical and effective brush gear for brushes which swing through the full polar arc whereby flexing of the leads connecting the brushes with the main lead terminals, or external circuit terminals, is entirely eliminated, whereby we are enabled to greatly reduce the cost of maintenance inclusive of inspection.

The foregoing, together with such other objects as may hereinafter appear, or are incident to our invention, we obtain by means of a construction which we have illustrated in preferred form in the accompanying drawings, wherein—

Figure 1 is an end elevation of a dynamo suitable for train lighting purposes, in which the end cap or dust covering is removed so as to expose the brush rigging; Fig. 2 is a section taken on the line 2—2 of Fig. 1, but with the dust cover in position; Fig. 3 is a section through half of the brush rigging

taken on the line 3—3 of Fig. 1; while Fig. 4 is a diagram showing the manner in which the device operates eliminating the flexing of the leads as hereinbefore noted.

While of course it is to be understood that our invention is applicable to dynamo electric machines of various types, we have illustrated our invention as applied to a dynamo for generating current to supply the batteries and the customary circuits of a train lighting system such as used on railway and other vehicles. Our invention is particularly valuable for two-pole machines, for it makes it possible to use the rotating type of brushes with such machines. We have therefore specifically shown our invention as applied to this type of dynamo in which the brushes swing through the full polar arc of 180°. It will be at once apparent to those skilled in the art that the improvements may be applied to a four-pole machine, for example, or other multi-polar machine.

Referring now particularly to Figs. 1 and 2, the numeral 7 denotes the magnet frame of the dynamo in which the armature spindle or shaft 8, the commutator 9, and the armature 10 are rotatably mounted in suitable bearings. A front head or ring 11 is secured to the outer face of the casing 7 which accommodates the forward end of the armature shaft with its bearing A. This bearing A is of the ball bearing or any other preferred type. The two carbon brushes B and C (generally indicated in Fig. 1 and specifically in Fig. 3) are mounted in the brush holders 12 which in turn are secured to the rocker 13 which in turn is mounted on ball bearings 15 on the ring portion 14 of the front head. The brush holders are secured to the rocker 13 by means of the studs 16 and 17, the brush holders being insulated from the rocker 13 by means of insulation plates 18, and insulated from the studs 16 and 17 by insulating sleeves 19. Projecting from the rocker 13 is a stop pin 20 adapted to come against either one of the two stops 21 at extremes of rotation through the full polar arc. The stops 21 are formed on the front housing. By this arrangement, the movement of the brush holders in either direction is limited at the proper place to secure good commutation. It will be understood of course that the carbon brushes B and C are yieldingly held in engagement with the commutator 9

y suitable spring mechanism such as that shown, and that the frictional engagement of the brushes with the commutator is sufficient to cause the brush rigging to reverse through the full polar arc upon reversals in the rotation of the armature.

On the end of the front head is screwed an end plate 23 or switch board on which are supported the positive and negative terminals 24 and 25, such terminals being insulated from the end plate by means of the insulation 26. The means whereby current is conducted from the brushes to the main or external circuit terminals 24 and 25 will 10 now be described.

The brush holder 12 for the brushes B carries two brass or copper extension members or arms 27 and 28, such arms being secured in place by the same studs 16 and 20 17 which serve to fasten the said brush holder 12 to the front head (see Fig. 3). The arm 27 is in electrical contact with the brush holder 12 but is insulated from the studs 16 and 17 by means of the insulating 25 sleeves 19. The arm 28 is insulated from the arm 27 and also from the said brush holder 12 by means of the insulation 29 and it is insulated from the studs 16 and 17 by the insulating sleeves 30, the plate 31 30 against which the heads or nuts of the studs abut when all the parts are tightened up, is insulated from the parts thus far described by means of the insulation 32. The arms 27 and 28 have their end portions 27^a 35 and 28^a bent downwardly and spaced apart and are apertured to receive a small shaft or spindle 33 which is provided with an insulating sleeve 34, the nut 35 for securing the spindle being also insulated from the portion 27^a. Mounted on the insulating sleeve 34 between the portions 27^a and 28^a of the arms is a round contact piece 36 which is in electrical contact with the extension 27^a, but is insulated from the extension 28^a by means 40 45 of the insulating disk 37. Mounted on the sleeve 34 on the outside of the extension 28^a, but in electrical contact therewith is a second round contact piece 38 which is insulated from the head of the shaft 33 by the 50 insulating disk 39.

Mounted on the end plate 23 is a second shaft or spindle 40, the position of which is to be hereinafter more specifically pointed out. On the shaft 40 is an insulating sleeve 55 41 which carries the following parts: namely, the positive main terminal 24, (insulated from the end plate 23 by insulation 26); the round contact piece 43 which is in electrical contact with the terminal 24, the 60 main or external negative terminal 25 (insulated from the contact piece 43 by the insulating disk 44); the contact piece 45, in electrical contact with the terminal 25, but insulated from the head or end of the shaft

40 by the insulating disk 46. The terminal 65 25 is stepped or bridged as at 25^a so that it can be securely fastened to the end plate or switch board 23 by the screw 25^b. The terminal 24 is similarly secured. By the foregoing arrangement, it will be seen that the 70 parts are so arranged and mounted that access can be readily had to the bearing parts, and that the various parts can be readily assembled or taken apart.

Electrical connection is had between the 75 contact piece 36 and the contact piece 43 by means of the flexible strap 47 and electrical connection between the contact piece 38 and the contact piece 45 is had by the 80 flexible strap 48. These straps (see Fig. 4) 85 are secured to the contact pieces by suitable fastening means such as the screws 49. The strap or yoke 50 (see Figs. 1 and 3) connects the brushes C with the arm 28. The path of current is as follows: Assuming that 90 the brushes B are positive, the current collected by the brushes B passes through the respective brush holder 12, through arm 27 and extension 27^a, through contact piece 36, strap 47, contact piece 43, terminal 24, 95 thence to the external circuit, returning by the negative main return to terminal 25, thence to contact piece 45, strap 48, contact piece 38, extension 28^a, arm 28, strap 50 to brushes C. Assuming now that the direction of train travel is reversed, the friction of the brushes on the commutator will cause the brush ring to reverse through the full polar arc until the pin 20 comes up against the respective stop 21. The signs of the 100 brushes will therefore remain the same. While the brush rigging is swinging through the full polar arc on reversals, the straps 47 and 48 will be wound on the contact pieces 43 and 45, the particular arrangement of the 105 stationary contact pieces with respect to the moving parts being as follows:

From inspection of Fig. 4 it will be seen that we have diagrammatically represented the fixed or stationary contact pieces at D; the movable contact pieces at E and the two connecting straps or leads at F; the center of the armature spindle at O; while E' represents the position of the movable contact pieces on the brush rigging when the 115 brushes have been reversed 180°, that is to say, when the position of the brushes is exactly transposed. The distance *a* which represents the distance between the center line of the armature spindle and the center 120 of spindle 40 is equal to one quarter of the periphery of the contact pieces 43 and 45; the distance *b* represents the distance between the center lines of the spindles 40 and 33; and the distance *c* represents the 125 distance between the center line of the armature spindle and the center of spindle 33, i. e., the distance *c* is the sum of the dis-

tances a and b . It will be seen therefore that when the contact pieces 36 and 38 are moved from the position indicated in full lines at E 180° to the position indicated in dotted lines at E', the straps 47 and 48, as represented at F, will assume the dotted line position between D and E'. Now, since the distance between the center lines at D and E' equals $c+a$ or $b+2^a$, which is the 10 length of the strap, it will be seen that the straps at no time are slack but simply unwind themselves on the stationary contact pieces, and that while the straps are wrapped around the stationary rollers, the 15 flexing is distributed over half the periphery of the stationary rollers, or over the distance equal to 2^a . Therefore in general, it may be said that the flexing of the leads or straps is negligible and can be considered 20 as non-existent in comparison to the flexing which takes place in standard switch gear constructions in which the brushes swing through the full polar arc.

The advantage of the arrangement will 25 be apparent to those skilled in the art, for it will be seen that it eliminates the difficulties which are encountered in standard constructions because of the flexing of the leads which connect the brushes with the external 30 terminals which results in frequent breakage and necessitates frequent examination and repair by maintenance force and avoids the careful location of the flexible leads otherwise necessary. At the same time the 35 construction is simple, inexpensive, short-circuiting is effectually prevented, and all parts of the apparatus at the commutator end of the machines are readily accessible for purposes of cleaning, repair or examination. As pointed out, the invention is 40 particularly valuable because it makes it possible to utilize rotating brushes on two-pole machines. A certain measure of the advantage incident to our invention may also be 45 obtained even if the spindle 40 is not eccentrically located.

We claim:

1. A reversing brush gear for dynamo electric machines comprising a rocking brush 50 holder, a lead for conducting the current having one end supported from said holder, and an anchoring member about which the other end of said lead is wrapped.

2. A reversing brush gear for dynamo 55 electric machines comprising a rocking brush holder, a lead for conducting the current having one end supported from said holder, and a stationary anchoring member located eccentrically with respect to the center of

rotation of the brush holder and about which 60 the other end of said lead is wrapped.

3. A reversing brush gear for dynamo electric machines comprising a pair of brushes, a rocking brush holder therefor, a pair of leads each of which is in electrical 65 connection with a brush and each of which is supported from the brush holder, and an anchoring member about which said leads are wrapped.

4. A reversing brush gear for dynamo 70 electric machines comprising a pair of brushes, a rocking brush holder therefor, a pair of supports at one side of said holder, one in electrical connection with one brush and the other with the other brush, a pair of 75 leads each connected to one of said supports, and a pair of stationary members about which said leads are wrapped.

5. A reversing brush gear for dynamo 80 electric machines comprising a pair of brushes, a rocking brush holder therefor, a pair of conductors mounted on one side of said brush holder and each having means for supporting a lead, one of said conductors being in electrical connection with one brush 85 and a strap for electrically connecting the other conductor with the other brush, a lead connection to each conductor, a pair of relatively fixed supporting means about which said leads are wrapped and means whereby 90 said supporting means are connected with external circuit terminals.

6. A reversing brush gear for dynamo 95 electric machines comprising a rocking brush holder therefor, a pair of conducting arms 100 mounted on said brush holder, one of said arms being electrically connected to one brush and the other to the other brush, a pair of drum-like lead supports mounted in said arms each of which is in electrical connection with one arm, a pair of relatively 105 fixed drum-like anchoring members, and a lead connecting each lead support to an anchoring member, said leads being wrapped about the anchoring members. 110

7. A rocking brush gear for dynamo 115 electric machines comprising a rocking brush holder, a lead for conducting current having one end supported from said holder and extending from the brush holder in a direction inward toward the center of rotation, and means for supporting the other end of said lead.

In testimony whereof we have hereunto signed our names.

H. D. ROHMAN.
F. R. PETERS
